UNITED STATES PATENT OFFICE

JACK H. BALCH, OF CHICAGO, ILLINOIS

FABRICATED GOLF CLUB HEAD

Application filed April 20, 1929. Serial No. 356,673.

This invention relates to improvements in the manufacture of golf club heads and particularly, to the manufacture of those types or designs of club heads whose constructions have been heretofore effected with wood—
 5 persimmon wood especially—such for example, as clubs identified in the parlance of the game as drivers, brassies and spoons, the invention having for its principal desiderata, to provide a fabricated club head, which, when constructed in accordance with the hereinafter more specifically disclosed teachings to the trade, will possess strength, rigidity and durability much greater than the now prevalent wooden club heads and also, 10 will approximate in weight, club heads constructed of persimmon or like generally used woods.

It is an equally important object of the invention to provide a fabricated golf club head, wherein the sheets or plys of material utilized in constructing the same, are so relatively arranged as to facilitate the correct shaping of the head and also, to impart a maximum of strength and durability to a 15 finished product, permitting the forming of the shaft receiving neck integral with the head and in a manner to ensure a practical degree of rigidity therebetween.

Other objects of the invention will be in part obvious and in part pointed out hereinafter.

In order that the invention and its mode of operation may be readily understood by 20 persons skilled in the art, I have in the accompanying illustrative drawing, and in the detailed following description based thereon, set out several possible embodiments of the same.

In the drawing:

Figure 1 is a vertical longitudinal section through a fabricated golf club head constructed in accordance with the invention, showing the same prior to vulcanization of 25 the layers or plys of fabric together;

Figure 2 is a similar section showing the golf club head subsequent to vulcanization of the layers or plys of fabric together and illustrating the attachment of a sole or wear 30 compensating plate to the sole portion of

the club as well as a means for lessening the weight of the completed product that it will approximate the weight of light wood clubs;

Figure 3 is a side elevation of a finished club head, constructed in accordance with the 35 invention, and

Figure 4 is a bottom plan view of the completed club head, showing the formation and the mode of attachment of the sole or wear compensating plate to the sole portion of the 40 club.

Having more particular reference to the drawing, in connection with which like characters of reference will designate corresponding parts throughout, the improved 45 golf head is preferably fabricated from layers or plys of canvas duck or other approved fabric, as is generally shown in the Figure 1, these layers or plys of fabric being arranged in superimposed relation with respect to each other, whereby to effect a building up of the club head construction; certain of these plys of fabric being in lengths such as will permit them to extend from the toe portion of the club throughout the club head neck and to 50 the extreme free end thereof, while others of these layers or plys of fabric are in lengths such as will permit them to extend from the toe portion of the club head to the base of the shaft receiving neck. The various layers or 55 plys of fabric employed in the fabricating of the golf club head are preferably of widths corresponding to the desired width of a club head to be constructed therefrom, though in this connection, it is to be understood, that 60 the layers or plys of fabric may be of different widths and that any number of the same may be employed to effect the constructing of a golf club head of a certain predetermined width, such as conditions or preference may 65 dictate.

The canvas duck or other fabric utilized in the construction of my improved golf club head, of course, is selected according to the 70 weight and character of fabric best suited for these particular purposes and such sheets or bodies of fabric, in the process of construction of the improved golf club head, are first thoroughly impregnated with a 75 bakelite varnish or similar resin, whereupon 80

the so impregnated fabric bodies are cut into strips of proper length and then placed aside for a time to permit of their drying.

The dried bakelite varnish or resin impregnated strips of fabric are then punched or cut into pieces of the required size and shape. Certain of these punched or cut pieces of the treated fabric are of lengths such as will permit them to extend from the toe portion of the club head to the free extremity of the shaft receiving neck, these pieces being generally indicated for convenience, at this time, by the numeral 1. Others of the cut or punched pieces of treated and dried fabric are of lengths such as will permit them to extend from the toe portion of the club head to the base portion of the shaft receiving neck and these shorter lengths of treated fabric are indicated for convenience, at this time, by the numeral 2.

The golf club head construction is started with the laying of the longer pieces of treated fabric indicated by the numeral 1 into the separated halves of an appropriate mold, whereupon shorter pieces of the treated fabric, such as indicated by the numeral 2, are superimposed upon the longer pieces 1. Longer pieces of the treated fabric, such as indicated by the numeral 1 are then laid over the uppermost shorter pieces 2 and this method of alternate laying of long and short pieces of treated fabric, 1 and 2 respectively, is continued until the separated mold halves have been supplied with superimposed layers of fabric representing the required thickness or depth of a golf club head to be molded therein.

With the alternate building up of the long and short pieces of treated fabric 1 and 2, in the sections of the golf club head mold employed, said mold sections are jointed, that is, the upper half of the mold is joined to the lower half thereof and at this time, the fabricated construction within the mold is subjected to a pressure of approximately three thousand pounds to the square inch and at the same time the mold is brought to that temperature necessary to effect a vulcanization of the plastic composition treated pieces 1 and 2 contained therein. While under the pressure indicated above, the fabricated construction within the mold is baked or cured for a period of from three to four hours, after which the heating of the mold is discontinued and the vulcanized product in form of the fabricated golf club head, then removed from the mold in complete form.

In this connection, it will be understood that the normally upper and lower sides of the completed and removed golf club head are faced with the longer pieces of fabric, hereinbefore identified by the numeral 1, thus giving a continuity of surface to the exposed faces or sides of the construction. By reason of the alternate laying or positioning of

the shorter pieces of treated fabric 2, it will be understood that the greater width or depth of the body portion 3 of the golf club head will be compensated for and that by the same token, the lesser width or thickness of the shaft receiving neck 4 of the club head will be compensated for. That is to say, since the shorter plies of treated fabric 2 terminate at points adjacent the base of the shaft receiving neck 4, the necessary reducing of the neck portion 4 may be practically effected with the subjection of the fabricated construction to pressure within the vulcanizing mold. At the same time, it will be understood and appreciated by workers skilled in this particular art, that the shaft receiving neck 4 will be integral with the body portion 3 of the club head and consequently upon this, that a maximum degree of rigidity will be effected as between these two particular elements, therefore, assuring effectual usage of a completed club head.

With the molding of the fabricated club head, the shaft receiving neck 4 may, of course, be formed with an opening of proper length and diameter for receiving the club shaft; this being effected by drilling or by similar ways and means, well known in the art.

In order that the weight of the molded club head may approximate the weight of the lighter wood clubs, I have found it practical, under such conditions, to hollow out a portion of the body 3 in the fashion as is indicated by the numeral 4'. This hollowing out of the golf club head body is effected from the normally lower side or heel portion of the same to, preferably within one-eighth of an inch from the normally upper side of said body, or if not this, then to such extent as will bring the weight of the club to approximately the same weight as a golf club head constructed from persimmon wood, which, as will be well understood, is generally used in this particular art at the present time.

A sole or wear compensating plate, preferably formed of aluminum, and generally indicated by the numeral 5, is provided the construction and is adapted to be set in flush with the normally lower side or sole portion of the body 3 of the club head, as is well shown in the Figure 2, adjacent portions of the normally lower or sole side of the club being cut away to effect this flush in-setting of the plate. Screws or other suitable fastening devices, generally indicated by the numeral 6, are passed through appropriately arranged openings formed in portions of the wear compensating plate 5 into engagement with adjacent portions of the body 3 and obviously, serve as means to effect a firm and positive securing of the plate to the head. Likewise, it will, of course, be understood that the opposite end portions of this wear com-

pensating or sole plate 5 are formed to correspond to the shape or curvature of the adjacent receiving portions of the opposite sides of the club head, as is shown in the Figure 4.

5 Under certain conditions, it may be desirable that the wear compensating plate 5 shall be of solid construction, so that when it is engaged flushly in the sole 5 of the club head body 3, it will serve as an effectual plate 10 closure for the hollowed out portion of the body, hence, preventing the possibility of dirt or other foreign accumulations therein with the resultant unbalancing of the club head.

It will be understood that golf club heads of 15 those particular types known in the parlance of the game as drivers, brassies and spoons, may be constructed in accordance with the invention herein disclosed, merely by the substitution of one character of mold for another, 20 whereby to effect the proper shaping of the desired club head construction.

Furthermore, and as stated hereinbefore, the layers or plys of treated fabric identified by the numerals 1 and 2, may be of different 25 widths and these layers, during the building up process of the fabricated head construction, may be arranged in juxtaposed relation so that one superimposed layer will be staggered in the jointures between the fabric 30 pieces constituting the same, with relation to the jointures of the adjacent superimposed layer. Likewise, it is to be understood that according to the thickness or depth of the body portion of a club head fabricated in accordance 35 with the invention, the number of shorter treated pieces 2 may be increased or decreased, such as conditions or preference may dictate and similarly, the number of the longer pieces of treated fabric indicated here- 40 in by the numeral 1 may be either increased or decreased to meet the particular requirements of construction.

Manifestly, the construction shown is capable of considerable modification, and such 45 modification as is within the scope of my claims I consider within the spirit of my invention.

I claim:

1. A golf club head comprising a body and 50 a shaft receiving neck composed of superimposed layers of fabric impregnated with a plastic composition and vulcanized together, certain of said layers of fabric being of lengths to extend from the toe of the body to 55 the free end of the neck and being curved transversely of themselves adjacent the heel of the body whereby to constitute said neck as an integral portion of the body, and the others of said layers being alternately ar- 60 ranged with respect to the first mentioned layers and being of lengths to extend from the toe to the heel of the body, said neck being formed for connection with a club shaft.

2. A golf club head comprising a body hav- 65 ing a shaft receiving neck extended there-

from, said body and neck being composed of superimposed layers of mesh material, said layers of material being arranged in relative overlapping relationship and certain of the same extending from the toe of the body to 70 the outer end of said neck, said layers of material being impregnated with a plastic matter and vulcanized together.

3. A golf club head comprising a body and a shaft receiving neck extended therefrom 75 the body and neck being composed of relatively superimposed layers of fabric, certain of which are formed in lengths extending from the toe of the body to approximately the base of the neck, others of said layers of fab- 80 ric being formed in lengths extending from the toe of the body to the outer end of said neck, the different lengths of fabric layers being disposed alternately in their superimposed relation and all of said layers being 85 transversely curved upon themselves adjacent the basal portion of the neck to afford the same with a substantially cross sectionally circular shape, and the layers of fabric being impregnated with a plastic matter and vul- 90 canized together.

4. A golf club head comprising a body and a shaft receiving neck composed of relatively superimposed layers of fabric, the lengths of said layers of fabric being different and 95 some thereof extending throughout the length of said body and for a distance into said neck and others thereof extending throughout the complete lengths of said body and said neck, said layers of fabric being im- 100 pregnated with a plastic matter and vulcanized together, and the body being brought to required weight by cutting away an intermediate portion of the same from the normally lowered side thereof.

5. A golf club head comprising a body and a shaft receiving neck, said body and neck being composed of a plurality of relatively superimposed pieces of mesh material of different sizes arranged in overlapping relationship, the neck formed by said pieces of mesh material being integral with the body of the head and said pieces of mesh material being impregnated with a plastic matter and vulcanized together.

6. An article of manufacture consisting of a golf club head comprising a body and a shaft receiving neck, said body and neck being composed of a plurality of relatively overlying pieces of mesh material, the neck being formed upon one portion of the body by extending certain of the pieces of material therefrom, and said pieces of mesh material being impregnated with a plastic matter and vulcanized together to provide a hard, sub- 120 stantially rigid and non-warping device throughout its area.

7. A golf club head comprising a body and a shaft receiving neck extended from a portion thereof, the body and neck being com- 125 130

posed of relatively overlying pieces of fabric, portions of certain of the pieces of fabric being transversely curved upon themselves in proximity to the basal portion of the neck to afford the same a substantially cross sectionally circular shape and the pieces of fabric being impregnated with a plastic matter and vulcanized together.

In witness whereof I have hereunto set my
10 hand.
